UNITED STATES PATENT OFFICE.

URIAH R. McCUTCHEN, OF SPRINGFIELD, ILLINOIS, ASSIGNOR OF ONE-THIRD TO JOHN A. BRYDEN AND ONE-THIRD TO JAMES A. HALL, BOTH OF SPRINGFIELD, ILLINOIS.

GASOLENE SERVICE-STATION.

1,387,421.

Specification of Letters Patent.

Patented Aug. 9, 1921.

Application filed April 15, 1919. Serial No. 290,202.

To all whom it may concern:

Be it known that I, URIA R. McCUTCHEN, a citizen of the United States, residing at Springfield, in the county of Sangamon and State of Illinois, have invented certain new and useful Improvements in Gasolene Service-Stations; and I do declare the following to be a full, clear, and exact description of the invention such as will enable others skilled in the art to which it appertains to make and use the same.

My invention relates to that class of liquid dispensing apparatus (particularly gasolene service stations) in which the liquid is introduced by a vacuum line or otherwise into an elevated dispensing and measuring container and discharged from the latter by gravity. Several systems of this general type have been heretofore devised but my invention has for one of its foremost objects to simplify the construction of such systems, particularly by dispensing with the separate float chamber heretofore employed for operating the cut-off valve for the vacuum line; and by locating said vacuum line in a much more desirable manner for ease of manufacture, assembly, repair, etc.

In the improved apparatus, an overflow line is provided to drain all liquid in excess of a predetermined quantity, from the dispensing container before opening the outlet of the latter, and a further object is to provide means to prevent passage of liquid through said overflow until the float valve has been closed by such liquid to cut off the suction.

Another object is to make novel provision for draining the entire system each night, or whenever its use is discontinued, thus leaving no liquid above ground. This is of particular advantage in gasolene service stations or when the apparatus is used for dispensing other highly volatile and explosive liquids.

Yet another object is to provide a housing for parts of the system having a door which must be opened before the system can be operated, novel means being provided for preventing drainage of the system when said door is opened and for permitting such

drainage when the door is shut, for instance, when the service station is closed at night.

A still further object is to provide a single check valve in a combined supply and drainage line for preventing drainage when the system is in use but for permitting such drainage when operation of the apparatus is discontinued.

With the foregoing objects in view, the invention resides in the novel construction and arrangement of parts as hereinafter fully described and claimed, reference being made to the drawings described below.

Figure 1 is a front elevation partly in section of a gasolene service station constructed in accordance with my invention showing the housing open for use.

Fig. 2 is a detail elevation illustrating the door above mentioned in closed position.

Fig. 3 is an edge view of the service station with parts in section.

Fig. 4 is a perspective view illustrating more clearly the arrangement of the numerous pipe lines and their association with the dispensing containers, a vacuum tank and supply tank.

Fig. 5 is an enlarged vertical transverse section through one of the dispensing containers and associated parts.

Fig. 6 is an enlarged longitudinal section of the check valve which normally prevents return of liquid through the supply piping, showing also the means for holding said valve open when the aforementioned door is closed.

Fig. 7 is a perspective view similar to Fig. 4 but illustrating another form of the invention.

Briefly speaking, the system consists of a supply tank 1, preferably located below the surface of the ground; a vacuum tank 2; a frame structure or the like 3 supporting one or more measuring and dispensing containers 4; piping and valves for controlling the suction, the supply and discharge of liquid, the overflow from the containers, and the drainage of the entire system; together with other novel features all herein-after described.

The vacuum tank 2 may well form a base

for the portion of the apparatus above ground, and a motor driven pump (not shown) is provided for maintaining the vacuum in said tank. A housing 7 is provided at the lower end of the frame structure 3, said housing having a downwardly swinging front door 8 and an end door 9, the latter being preferably formed of two sections hinged together as shown clearly 5 in Figs. 1 and 2, and brackets 10 may well be provided for limiting the opening movement of said door 9 to form a convenient shelf of the inner section thereof. When the two doors 8 and 9 are closed, the numerous 10 parts of the system are inaccessible and consequently the apparatus cannot be operated, and it may here be stated that although two doors are preferably provided, only one need be used in some instances. In most forms 15 of my invention, one door is essential, not only to give access to the controls of the system, but to operate the valve which either prevents or allows drainage of the system.

The frame structure 3 may be of any adequate formation but preferably includes upright corner posts 11 and a roof 12 which may well carry electric lights 13. Similarly, the exact shape and design of the dispensing and measuring containers 4 may vary as 20 occasion may dictate, but I prefer to form said containers of glass jars having outlet necks 14 seated in a fluid-tight manner in appropriate couplings 15 which may well rest on the top of the housing 7. The upper 25 ends 16 of the containers 4 are preferably removable and gaskets 17 are provided to prevent leakage, and although any preferred means could be employed for clamping the ends 16 in place, I have shown a crown plate 30 secured by bolts 19 to the corner posts 11. This crown plate may support the roof 12 by means of vertical posts or the like 20.

A vacuum line 21, in the preferred form 35 of my invention, leads from the vacuum tank 2 to the upper end of each container 4 and at the juncture of each vacuum line with its respective container, a valve 22 is provided, closable by the rising liquid in the container, through the instrumentality 40 of a float 23, which may well be connected to the valve proper by a stem 24. By locating the float 23 directly in the upper end of the container 4 and positioning the vacuum line 21 on the exterior of said container, the 45 construction of the apparatus is greatly simplified over similar systems which have heretofore been devised.

Preferably, each float 23 will be housed 50 within an open cage 25, but it will be understood that the type of float, the form of valve, and the mountings of these parts, may well vary in numerous ways.

Depending from each container 4 is a 55 four-way coupling C having one upwardly and one downwardly extending branch 26

and 27 respectively and two laterally extending branches 28 and 29. The upwardly projecting branch is connected to the coupling 15, and the branches 28 of the two couplings serve as fuel outlets into piping 30 from 70 which the usual hose 31 extends, a valve 32 being positioned between each coupling C and said hose, in order that operation of one unit of the apparatus will not affect the other. An overflow pipe 33 passes through 75 each coupling C and rises into the container 4 to such a height as to allow any liquid over a predetermined amount, five gallons for instance, to drain from said container. It will be observed that sufficient space 34 80 exists between the overflow 33 and the branch 26 to allow the liquid to discharge through the latter and it will also be seen, (reference being made more particularly to Fig. 5,) that the pipe 33 passes adjustably 85 through the branch 27, being held in adjusted position by a locknut 35. A gasket 36 is provided between the nut and the branch 27 to prevent any possibility of leakage. It is intended that an authorized Government 90 inspector shall adjust the overflow 33 properly to prevent drainage of an improper amount of liquid from the container 4, prior to vending of such liquid to a customer, and when once set, the nut 35 may be held 95 against tampering by a seal 37.

In order to allow operation of the apparatus in the required manner, it is necessary to supply slightly more than the proper amount of liquid to the container 4, the surplus then draining out through the pipe 33. Before this drainage takes place however, the float 23 is raised by the liquid to close the valve 22, thus cutting off the vacuum line from the container. 105

The features so far described are identical in both forms of the invention, but separate descriptions of the other features thereof will be necessary.

In the type of the apparatus disclosed in 110 Figs. 1 to 6, supply piping 38 leads from the supply tank 1 to the branch 29 of one of the couplings C, while a branch 39 leads from such piping to branch 29 of the other coupling. The piping 38 includes a valve 115 casing 40 (see Fig. 6). The casing 40 is provided with a valve seat 41 and a stuffing box 42, and a check valve 43 co-operates with said seat 41 to normally prevent return of liquid through the piping 38 to the supply tank 1. When the door 9 is closed however, it forces a rod 44 inwardly to prevent closing of the valve 43, said rod passing through the stuffing box 42 and being slidably received in a tubular guide 45 with which said 120 valve is provided. When the door 9 stands open, the rod and valve assume the relative positions shown in Fig. 6 and said rod will not prevent closing of the check valve when the container 4 has been filled with liquid, 130

but when said rod is shifted inwardly by closing of the door, it abuts the end of guide 45 and thus positively prevents closing of the valve 43, thus allowing all liquid from 5 the system to drain into the supply tank 1.

Any preferred means might be provided for operating the rod 44 from the door 9, but I preferably provide a slotted link 46 connecting the two for this purpose. When the 10 door 9 is closed, the link 46 stands as seen in Fig. 2 but when the door is opened said link pulls upon the rod 44 to return the latter to an inoperative position.

Piping 47 connects the lower ends of the 15 overflow pipes 33 and communicates at 48 with the supply piping 38, and in order that the excess liquid may not flow through either of the two pipes 33 until closing of the valve 22 of the filling chamber has taken place, 20 cut-off valves 49 are provided for the piping 47.

For manually discontinuing the suction through the vacuum lines 21, suitable valves 50 may be provided. If the suction is of 25 sufficient strength to hold the valve 22 closed while the container 4 is discharging, each valve 50 may be provided with a vent 51 and it will thus be seen that when discharging 30 of the liquid is complete, closing of the valve 50 to cut off suction through the suction line 21, and simultaneous opening of the vent 51 will allow atmospheric air to enter and relieve the vacuum acting upon valve 22, thus allowing the latter to drop to open position. 35 It will be seen that the vent 51 and the upper portion of the vacuum line 21 will supply sufficient air to the upper end of the container 4, to allow discharge of the liquid therefrom.

40 Although I intend the use of an ordinary two-way valve at 50, any other preferred valve could be used, but it would then be necessary to provide other means for admitting air into the upper end of the container 4 and for releasing the valve 22 if the suction in the apparatus is sufficiently strong to retain the same in closed position as the liquid discharges.

In the form of the apparatus disclosed in 50 Fig. 7, supply piping 52 leads to the branches 29 of the couplings C from the supply tank 1 and to prevent the return of liquid through this piping, check valves 53 are provided therein. Piping 54 connects the lower ends 55 of the overflow pipes 33 and discharges into the fuel tank 1, a branch pipe 55 depends from the piping 52 adjacent one coupling C, extends laterally at 56 and communicates with the piping 54, and leading from said 60 piping 52 at a point adjacent the other coupling C, is a pipe 57. An ordinary cut-off valve 58 is located in the horizontal part 56 of the piping 54 and is provided with an operating arm 59 which is loosely linked at 65 60 to the door 9. When the door is opened

for use of the apparatus, the valve 58 is closed, but when said door is closed, the valve in question is opened, thus allowing the entire system to drain. As in the form of the device above prescribed, cut-off valves 61 are 70 provided to prevent passage of the excess liquid through the overflow pipes 33 until operation of the floats 23, said valves being located in the piping 54.

Valves 50' are shown in the vacuum lines 75 20 in Fig. 7 for performing the same functions as the valves 50, said valves having vents 51'.

The operation of the first described form of the invention (shown in Figs. 1 to 6) is as 80 follows:

The door 9 is opened, thereby moving rod 44 to an inoperative position. The valves 32, 49 and 50 now stand in closed position, but when said valve 50 is opened, the vacuum 85 tank 2 and the vacuum line 21 will exhaust the air from the upper end of the container 4, thus drawing liquid upwardly through the piping 38 and the check valve casing 40, into the coupling C and from the latter into said 90 container 4. When the liquid rises in the container to a sufficient height, it raises float 23 and closes valve 22, thus cutting off the suction through the vacuum line. If the suction is insufficient to sustain the float when 95 the liquid is discharged from the container 4, the valve 50 is now immediately closed, but otherwise closing may be delayed. The valve 49 is now opened, thereby allowing the excess liquid to drain through the overflow 100 pipe 33 to the piping 38 for discharge into the tank 1. This having been done, the valve 32 is opened, thus allowing the liquid to discharge from the container 4 through the piping 30 and hose 31. If the valve 50 is 105 not closed at the completion of the filling operation of the container 4, thereby opening the vent 51 and allowing air to enter the upper end of said container as the liquid discharges, some other adequate provision must 110 be made for this purpose.

When the door 9 is shut, for instance when the service station is closed at night, the rod 44 is pushed inwardly and holds the valve 43 against closing, thereby allowing the entire system to drain into the supply tank 1.

The operation of the apparatus shown in Fig. 7 is very similar to that above described, the liquid being introduced into the 120 containers through the piping 52 and the check valves 53. Drainage however takes place through the valve 58 when the door 9 is closed.

If the apparatus be provided with the 125 two doors 8 and 9, the former will permit the hose 31 to be positioned in the housing 7 when the system is locked for the night or whenever its use is to be discontinued, but it is to be understood that in some forms 130

of the invention, two doors are not essential. Also, regardless of the several specific details shown and described, numerous minor changes may well be made, but I attach great importance to the general simplification of construction; to the provision of the valves to prevent overflowing of the liquid until the float valves have closed; upon the novel drainage means employed; and upon 10 the door operated valve for controlling such drainage means.

I claim:

1. A liquid dispensing system comprising a dispensing container, a supply tank, supply piping from said tank to said container, a liquid-operated check valve for said piping, a vacuum line on the exterior of said container adapted to exhaust the air from said container to cause filling thereof through 15 said piping, an overflow from said container, a float valve whose float operates in said container for cutting off the suction through said vacuum line at each operation of the system when the liquid level in said 20 container has risen to the inlet of said overflow, a valve for said overflow adapted to remain closed while said vacuum line is operating to exhaust the air from said container, and a valved outlet from said container.

2. In a liquid dispensing system, a dispensing container, a supply tank, a pipe coupling having two horizontally opening branches, one downwardly opening branch 35 and one upwardly opening branch, the latter communicating with said container, a supply pipe from said tank to one of said horizontally opening branches, and a valved outlet pipe from the other horizontal 40 branch, a liquid-operated check valve for said supply pipe, an overflow pipe extending through said coupling in spaced relation to said upwardly and horizontally opening branches but secured snugly in and depending 45 from said downwardly opening branch to return excess liquid to said supply tank, a vacuum line on the exterior of said container and communicating with the upper end thereof, a valve having a float operating 50 in said container at each operation of the system for cutting off the suction through said vacuum line when the liquid level in said container has reached the inlet of said overflow, and a valve for said overflow 55 adapted to remain closed while said vacuum line is operating to exhaust the air from said container.

3. In a liquid dispensing system, a dispensing container having outlet means and 60 a supply tank below said container, supply piping from said tank to said container, and means for supplying said container with liquid by way of said piping, a valve in said supply piping for normally preventing 65 return of liquid through said piping, a hous-

ing for parts of said system having a door to be closed when operation of said system is to be discontinued, and means for controlling said valve from said door to hold the former against closing when said door 70 is closed, whereby drainage of the system may take place through said piping.

4. In a liquid dispensing system, a dispensing container having outlet means, and a supply tank below said container, supply 75 piping from said tank to the lower end of said container, and means for supplying said container with liquid by way of said piping, a check valve in said supply piping for normally preventing return of liquid through 80 said piping, a housing for parts of said system having a door to be closed when operation of said system is to be discontinued, and means for controlling said check valve from said door to hold the former against 85 closing when said door is closed, whereby drainage of the system may take place through said piping.

5. In a liquid dispensing system, a dispensing container having outlet means, and 90 a supply tank below said container, supply piping from said tank to the lower end of said container and means for supplying said container with liquid by way of said piping, a check valve casing in said piping having 95 a valve seat and a stuffing box, a check valve coacting with said seat to normally prevent return of liquid through said piping, a housing for parts of said system having a door adapted to be closed when operation of the 100 system is to be discontinued, a stem sliding through said stuffing box and shifted by closing of said door to hold said valve in open position, whereby drainage of the system may take place through said piping, and 105 means for returning said stem to its inoperative position when said door is opened.

6. In a liquid dispensing system, a dispensing container having outlet means, and 110 a supply tank below said container, supply piping from said tank to the lower end of said container, and means for supplying said container with liquid by way of said piping, a check valve casing in said piping having 115 a valve seat and a stuffing box, a check valve coacting with said seat to normally prevent return of liquid through said piping, a housing for parts of said system having a door adapted to be closed when operation of the system is to be discontinued, a stem sliding 120 through said stuffing box and shifted by closing of said door to hold said valve in open position, whereby drainage of the system may take place through said piping, and linkage connecting said door and stem for 125 returning the latter to its inoperative position when said door is opened.

7. A liquid dispensing apparatus comprising a dispensing container, a supply tank, a pipe coupling having an outlet and pro- 130

vided with a branch connected to and communicating with the interior of said container, a valved delivery pipe connected to said outlet and communicating with the interior of said container by way of said branch, a supply pipe for said container leading from said tank, a vacuum line on the exterior of said container adapted to exhaust the air from said container to cause liquid to flow from said tank to said container by way of said supply pipe, and an overflow pipe leading from said container through said pipe coupling in spaced relation to the wall of said branch thereof and secured to said pipe coupling, said overflow pipe communicating with said supply pipe.

8. A liquid dispensing apparatus comprising a dispensing container, a supply tank, a pipe coupling provided with an upwardly opening branch, a downwardly opening branch and a pair of horizontally opening branches, said upwardly opening branch being connected to and communicating with the interior of said container, a valved delivery pipe connected to one of said horizontally opening branches and communicating with the interior of said container by way of said upwardly opening branch, a supply pipe leading from said tank to the other horizontally opening branch and communicating with the interior of said container by way of said upwardly opening branch, a vacuum line on the exterior of said container adapted to exhaust the air from said container to cause liquid to flow through said supply pipe from said tank to said container, and an overflow pipe extending centrally through said coupling in spaced relation to said upwardly and horizontally opening branches thereof, said overflow pipe being secured snugly in and depending from said downwardly opening branch and communicating with said supply pipe at a point between its connection with said other horizontally opening branch and its connection with said tank.

In testimony whereof I have hereunto set my hand.

URIAH R. McCUTCHEON.
